UNITED STATES PATENT OFFICE.

SAMUEL TAYLOR BEARE, OF JACKSON, TENNESSEE.

REFRIGERATION.

Application filed October 12, 1927. Serial No. 225,862.

This invention relates to improvements in refrigeration and more particularly to a refrigerator structure, one object of the invention being to so construct a refrigerator 5 that a portion of a food compartment thereof may be opened and segregated from other portions of said compartments so as to prevent the entrance of warm air into the food compartments, except in that portion only 10 which may be opened for the reception or removal of food.

A further object is to utilize closures for portions of a food compartment, as means for interrupting the circulation of cold air 15 through said compartment and segregate one portion of said compartment which may be opened, from other portions thereof.

A further object is to provide a refrigerator in which a freezing and cooling unit is 20 removably located in a chamber thereof and adapted to serve the double purpose of cooling the air which circulates through the refrigerator and to freeze material contained within said freezing and cooling unit.

With these and other objects in view, the invention consists in certain features as hereinafter set forth and pointed out in the 25 claim.

In the accompanying drawings,—
30 Figure 1 is a perspective view of a refrigerator showing an embodiment of my invention,—the doors of the refrigerator being shown open.

Figure 2 is a view partly in front elevation and partly in section with the hinged doors removed, and

Figure 3 is a vertical transverse section through that portion of the refrigerator in which one of the food chambers is located.

The casing or body portion of the refrigerator is indicated at 1 and is divided by a vertical partition 2 to provide a vertical food compartment 3 at one side and a food compartment 4 and a cooling compartment 5 at the other side of said partition. The compartments 4 and 5 are divided by a horizontal partition 6 having an opening 7 surrounded by a flange 8 projecting upwardly into the cooling compartment 5. An opening 9 in the vertical partition 2 affords communication between the upper portion of the food compartment 3 and the upper portion of the cooling chamber 5 and an opening 10 in the lower portion of said partition affords communication between the food 55 chambers 3 and 4. The partition 6 affords a floor for the cooling chamber 5 and upon this floor brackets 11 are located and provided with flanges which afford trackways 12 to receive and support a cooling and freezing unit 13 located within the chamber 5,—the upper portions of said brackets forming guides for said freezing and cooling unit. The cooling and freezing unit consists of a tank to contain broken ice and salt and is 60 adapted to receive drawers 14 in which material to be frozen will be placed. In the drawing I have shown a shelf 15 supported by posts 16 and disposed above the surface of the floor 6 and a block of ice 17 placed upon said shelf. It may be here stated however that the placing of a block of ice in the compartment 5 is not essential to the operation of the refrigerator, as the unit 13 containing broken ice and salt will serve to cool 65 the air circulating through the refrigerator. It will be understood that the air will pass from the cooling chamber 5 through the opening 7 and downwardly through the food compartment 4, then through the opening 10 in the lower portion of the partition 2 and into the lower part of the vertical food chamber 3 and from the upper part of the latter, through the opening 9 in partition 2 and into the upper portion of the cooling chamber 5 as illustrated by the arrows in 70 figure 2.

The cooling chamber may be closed by a hinged door 18 and the food chamber 4 below the cooling chamber may be closed by a hinged door 19 preferably having a glass panel 20. The door 18 may also be provided with a glass panel 21, if desired. The food compartment 4 contains a reticulated or wire tray or shelf 22 mounted on supports 23.

The vertical food compartment 3 is closed by an outer hinged glass paneled door 24 and a series of superimposed and spaced reticulated trays or shelves 25 are located within said chamber 3. The supports for these trays or shelves consist of channeled members 26. These channeled members or certain of them provide supports and guideways for supplemental doors or closures 27 for the vertical food compartment 3. Each of these closures 27 may be provided with a glass panel 28. When access to any part of the food chamber 3 is desired, one of the supplemental closures 27 may be raised to a horizontal position and slid back through its 100 105 110

guideways 26 and caused to interrupt the circulation of cold air through said chamber and prevent the entrance of warm air into said chamber 3 except into that portion 5 thereof which may be open. By interrupting the circulation through the vertical food compartment 3 as above described, warm air entering that portion of said compartment which may be open will be prevented from 10 reaching the cooling chamber 5 to an appreciable extent.

Having fully described my invention what I claim as new and desire to secure by Letters Patent, is:

15 A refrigerator comprising an outer casing, a vertical partition extending the full height of the casing and having openings near its upper and lower ends, a horizontal partition

at one side of the vertical partition whereby to form an ice chamber in the upper part of 20 the casing, said horizontal partition having an opening therethrough, an ice support over the opening in the horizontal partition, tracks on said partition between the opening therein and the vertical partition, and a cooling and freezing unit slidably mounted on said tracks and extending to the upper opening in the vertical partition whereby air passing into the ice chamber will be deflected downwardly and caused to flow under the 25 unit to the opening in the horizontal partition.

In testimony whereof, I have signed this specification.

SAMUEL TAYLOR BEARE.
